UNITED STATES PATENT OFFICE.

GUSTAVE W. MOELLER, OF HARRIS, IOWA.

ACCOUNTING AND RECORD DEVICE.

1,351,864.

Specification of Letters Patent. Patented Sept. 7, 1920.

Application filed November 14, 1918. Serial No. 262,501.

To all whom it may concern:

Be it known that I, GUSTAVE W. MOELLER, a citizen of the United States of America, and resident of Harris, Osceola county, 5 Iowa, have invented a new and useful Accounting and Record Device, of which the following is a specification.

The object of this invention is to provide an improved accounting and record device 10 particularly adapted for use in connection with public sales involving a considerable number of articles and purchasers.

A further object of this invention is to provide a flexible, elastic and convenient 15 form for keeping a record of articles sold, purchasers, prices and terms involved in a public sale.

A further object of this invention is to provide an improved open ended envelop 20 having on its face a printed form adapted to receive memoranda relative to individual sales of a series, said envelop containing a manifolding member and sheet adapted to receive a duplicate of said memoranda; said 25 envelop also containing a relatively heavy and stiff backing sheet, means being provided for receiving and holding a collocation of such envelops and their contents; the insert contents of said envelops being of 30 less length and spaced from the open end of the envelops by which the collocation is held, thereby permitting a flexing of the envelops for inspection, on lines between the contents and the holding device.

35 My invention consists in the construction, arrangement and combination of elements hereinafter set forth, pointed out in my claim and illustrated by the accompanying drawing, in which—

40 Figure 1 is a face view illustrating the complete device, with illustrative memoranda entered on the uppermost envelop. Fig. 2 is a side elevation of the same, dotted lines indicating possible flexed positions of 45 some of the envelops. Fig. 3 is a longitudinal section through one of the envelops and its contents. Fig. 4 is a face view of the upper portion of an envelop, partly in section to illustrate its contents.

50 In the construction of the device as shown a plurality of identical envelops 10 are employed, which preferably are formed of a tough quality of paper and are open at one end. The face of each envelop is printed 55 with a suitable form and contains a heading

with spaces for setting forth the identity or location and date and terms of the sale to be recorded, and beneath that columns and lines for entries and memoranda relating to "Article" sold, "Purchaser" and "Price." 60 Within each envelop, and in the orderd named from front to back thereof, are placed a carbon sheet 11, sheet 12 to receive duplicate of the memoranda entered on face of envelop, and a relatively heavy or stiff 65 backing sheet 13 to give stiffness to the whole and furnish a support for penciling the memoranda. A portable shelf or board 14 is provided and preferably is of some-what greater dimensions than the envelops 70 10 and is provided near one end with a spring clip 15 of any suitable form, adapted to receive and hold a collocation of loose sheets or members to the board.

In use any desired number of the 75 envelops 10 are placed on the face of the board 14 and held in place by the spring clip 15, each of said envelops preferably having been supplied with the memoranda indicat-ing the particular sale for which they are to 80 be used. Then as the sale progresses the clerk makes the entries in the columns of the envelops, starting with the outermost one of the collocation, thus keeping a record in duplicate of the articles sold, the pur-chasers and prices. The spring clip 15 is 85 designed to engage the open end portion of the envelops and not extend beyond nor engage in any manner the inclosures such as carbon sheet 11, second sheet 12 and back-ing sheet 13, thus engaging only two thick-nesses of each record device, namely the front and back sheets of the envelop there-of. Thus a greater capacity of the spring 90 clip is secured, and also a flexibility of the 95 record devices. As the contents of the envelops are not engaged by the spring clip, and particularly the stiff backing sheet 13, each envelop may be flexed away from the others and from the board 14, as indicated 100 by dotted lines in Fig. 2; flexing on trans-verse lines between the spring clip and the upper ends of the contents of the envelops, such as the dotted line $x-x$ in Fig. 4. This permits inspection of the record of any sub-jacent envelop, and addition to or correc-tion of such record, without removing the 105 overlying envelops.

As each article disposed of is paid for, or satisfactory arrangement for payment made, 110

a check mark may be entered by the clerk opposite the entry relating thereto; and in case the entry sought is not found on the uppermost envelop the search may be continued to the other envelops in turn by turning back the uppermost as shown and described. As each envelop is used up it may be removed from the top of the pile and slipped beneath by releasing the spring 5 clip. The engagement of the spring clip with the open end of the envelop prevents displacement or loss of any of the contents but at the same time permits ready access thereto when desired. When the sale is 10 concluded the duplicate records may be turned over to the proprietor while the originals are retained by the clerk or left at a designated bank or other place where settlement is to be made by the respective 15 purchasers.

I claim as my invention—

An accounting and record device, comprising a collocation of envelops each having indicia on its face suitably arranged to receive entries and memoranda, each envelop containing a carbon sheet, second sheet and backing sheet, said insert sheets being substantially shorter than the envelop, and a holding device engaging the collocation of envelops at those portions not occupied by the insert sheets, whereby the envelops, relatively stiff in their main portions, are free to flex on transverse lines between said holding device and the insert sheets. 25

Signed at Harris, in the county of Osceola and State of Iowa, this 8th day of October, 1918.

GUSTAVE W. MOELLER.
